FIG-4

FIG-5

INVENTOR

AUGUST T. NISWANGER
BY
Richard J. Cook
ATTORNEY

UNITED STATES PATENT OFFICE.

AUGUST T. NISWANGER, OF CHICAGO, ILLINOIS.

POST-HOLE-DRILLING MACHINE.

1,295,575.

Specification of Letters Patent.

Patented Feb. 25, 1919.

Application filed May 13, 1918. Serial No. 234,327.

To all whom it may concern:

Be it known that I, AUGUST T. NISWANGER, a citizen of the United States, residing at Chicago, in the county of Cook 5 and State of Illinois, have invented a new and useful Improvement in Post-Hole-Drilling Machines, of which the following is a specification.

This invention relates to improvement in 10 post hole drilling machines, and the object of this improvement is to provide a machine that can be actuated to drill post holes very quickly, either manually or by power.

15 A further object resides in the adaptability of the drilling mechanism to be shifted to various positions on the frame for centering the auger at the exact place of operation without moving the machine.

20 A still further object resides in the adaptability of the machine to be moved from place to place without having to be dismantled, and to be stationed for operation either on sloping or level ground.

25 Further objects will appear from the following specification, illustrated in the accompanying drawings and finally pointed out in the appended claims.

In the drawings, Figure 1 is a sectional 30 elevation of the machine with parts broken away;

Fig. 2 is an end view of the gears upon the crank shaft taken on line 2—2 of Fig. 3.

Fig. 3 is a sectional elevation of the differential mechanism taken on line 3—3 of Fig. 4.

And Fig. 4 is a plan view of the differential mechanism taken on line 4—4 of Fig. 1.

Referring more particularly to the drawings, in which like reference numerals indicate like parts, the numeral 1 represents the base of the machine as supported upon legs 2, and these legs are adapted to be telescopically adjusted in length by set screws 3. Upon the base 1 is pivotally attached an elongated member 6 that is disposed to project outwardly therefrom and having attached thereto, a supporting stabilizer 7 that is adapted to make contact with the ground through the medium of a wheel 8, and this wheel is adjusted to the lower end of the stabilizer 7 by a set screw 5 in such a manner as to be caused to face in various directions.

55 Superimposed upon the elongated member 6 are rigidly secured upright supports 9

upon which is mounted a transverse crank shaft 10 having a crank 11 for manual control attached to one end thereof.

12 is a gear fixedly secured to a sleeve 28 60 longitudinally movable upon the crank shaft 10, and 13 is a similar gear of smaller diameter fixedly secured to said sleeve in the same manner and is adapted to engage in meshing contact with a gear 14 rotatably 65 mounted upon a pinion 15 of a bracket 16 which is loosely interposed upon said sleeve intermediate the gears 12 and 13. This bracket 16 is held against rotary movement by two outwardly directed flanges 7' that 70 bear against the top of an inverted U-shaped bar 17 rigidly secured upon the outer end of the elongated member 6.

18 is a pipe shaft having threads upon its outer periphery and this shaft is vertically 75 disposed to project through slots provided in the bar 17 and the member 6 and is held in suspension by gear wheel 19 in meshing contact therewith and this gear wheel is disposed upon the pipe shaft between the 80 bar 17 and the member 6 and in bearing contact with the latter.

The pipe shaft 18 is provided with a bar 20 that extends therethrough and this bar is provided with a longitudinal groove 21 85 for the reception of a feather provided on the inner periphery of the sleeve 23 for keying the bar for longitudinal movement upon the sleeve. This sleeve is further provided with a cog gear 24 fixedly secured 90 thereto at its lower end and with a fixedly secured collar 25 at its upper end.

The pipe shaft 18 is also provided with a longitudinal slot 26 through which is projected the end of the crank shaft 10 and 95 upon the outer end of this crank shaft is attached a gear wheel 27 that engages with the cog gear 24 and is held in meshing contact therewith by an L-shaped member 27' loosely disposed upon the shaft 10 and the sleeve 23 100 in bearing contact with the collar 25 which is provided upon the sleeve for this purpose.

The lower end of the bar 20 is adapted to have attached thereto a collar 29 rigidly secured by a set screw 30 for the reception of 105 auger 31 which can be likewise held securely by set screw 32. The upper end of the bar 20 is also provided with a collar fixedly secured in bearing contact with the upper end of the pipe shaft 18 for sustaining the 110 bar against displacement.

The function of this differential mecha-

nism is for the purpose of causing the auger to penetrate the ground and be removed therefrom without reversing the direction of its rotation.

5 The mode of operation is accomplished in the following manner: The machine is manually wheeled to the place of operation and is tilted at an inclination from the vertical so that the weight will bear upon the 10 wheel of the stabilizer. The auger is then centered over the spot where the hole is desired to be bored by shifting the elongated member on its pivot and adjusting the set screw 33 which projects upwardly through 15 the circular slot 34 provided in the member 6 from its fixedly secured location upon the base 1.

Upon centering the auger at the proper place, a lever 35 which is pivotally attached 20 to the elongated member and engaging with a collar provided on the sleeve 28 is caused to be shifted until the gear wheel 14 is brought into meshing contact with the gear wheel 19 provided on the pipe shaft 18 rendering neutral by this shifting operation the 25 gear 12. The rotation of the crank shaft 10 also causes the bar 20 to move downwardly in unison with the pipe shaft 18 through the medium of the intermeshing gears 24 and 27 30 provided on the sleeve 23 and the crank shaft 10 respectively. The auger is thus caused to penetrate the ground to the depth desired.

To remove the auger without reversing 35 the direction of its rotation so as to remove the soil from the hole bored, the lever 35 is actuated to shift the sleeve 28 so as to bring in meshing contact the gear wheel 19 with the gear 12 which remained neutral in the 40 preceding operation and rendering neutral the gear 14. This operation simply reverses the direction of movement of the pipe shaft 18, causing it to move upwardly through its threaded engagement with the gear wheel 19 45 and lifting the auger without causing the direction of its rotation to be reversed.

It is obvious that various changes in the details of construction can be made within the scope of the following claims.

50 What I claim is new, and desire to protect by Letters Patent, is:

1. A post hole drilling machine comprising a frame structure, a horizontal member superimposed upon said frame and supported from the ground at one end thereof, a crank shaft supported upon said member and parallel therewith, a plurality of gears of different diameters adapted to be longitudinally movable upon said crank shaft, 55 and a fixedly secured gear upon the end thereof, a threaded pipe shaft provided with a longitudinal slot, said pipe shaft vertically disposed upon the outer end of said horizontal member, and a gear threaded 60 thereon alternately engageable with certain 65

of the gears of said crank shaft for reversing the direction of its rotation to move said pipe shaft upwardly or downwardly, a bar within said pipe shaft provided with a longitudinal groove, an auger adapted to be 70 attached to the lower end of said bar, a sleeve disposed upon said bar and engageable with said groove, a gear fixedly secured to said sleeve in meshing contact with the gear upon the end of said crank shaft, and a 75 collar for shifting the sliding gears of said crank shaft to alternately engage with the gear of said pipe shaft whereby said auger can be caused to penetrate the ground and be removed therefrom without reversing the 80 direction of its rotation.

2. A post hole drilling machine comprising a frame structure, a member pivotally mounted upon said frame structure, a crank shaft supported upon said member, a fixedly 85 secured gear upon one end thereof, a sleeve longitudinally movable upon said crank shaft and provided with a plurality of gears of different diameters, a threaded pipe shaft provided with a longitudinal slot, said pipe 90 shaft vertically disposed upon the outer end of said member, a gear for actuating said threaded pipe shaft and engageable alternately with certain of the gears of said crank shaft, a bar within said pipe shaft provided 95 with a longitudinal groove, an auger adapted to be attached to the lower end of said bar, a sleeve disposed upon said bar with means engageable with said groove, a gear fixedly secured to said last named sleeve in meshing contact with the gear upon the end of said crank shaft, and means for shifting the sleeve of said crank shaft to alternately engage with the gear of said pipe shaft whereby said auger will be caused to penetrate the 100 ground and be removed therefrom without reversing the direction of its rotation when said crank shaft is actuated.

3. A post hole drilling machine comprising a frame structure, a member pivotally 110 mounted and laterally shiftable upon said frame structure, a crank shaft carried by said member, a rotatable shaft provided with an auger upon the lower end thereof, said shaft vertically mounted upon the outer end 115 of said member, differential mechanism operatively connected to said rotatable shaft and adapted to be actuated by said crank shaft whereby said auger can be caused to penetrate the ground and be removed therefrom without reversing the direction of its 120 rotation.

4. A post hole drilling machine comprising a frame structure, an elongated member pivotally attached to said frame and shiftable in a radius from said pivot point, a crank shaft having a gear fixedly secured thereto at one end thereof, said crank shaft mounted upon said member and provided with a sleeve slidably longitudinally there- 125 130

upon, a plurality of gears of different diameters fixedly secured to said sleeve, a bracket loosely disposed upon said sleeve intermediate said gears and provided with a rotatably mounted gear engageable with the smaller gear of said sleeve, a pipe shaft vertically mounted upon the outer end of said member and provided with a longitudinal slot approximately the length thereof, a bar rotatably disposed within said pipe shaft and provided with a groove, a gear adapted to be longitudinally movable upon said bar in meshing contact with the gear upon the end of said crank shaft, an auger carried by the lower end of said bar, and means for shifting the sleeve of said crank shaft whereby the gears thereof will be caused to alternately engage the gear of said pipe shaft and actuate the same upwardly or downwardly when said crank shaft is actuated.

5. A post hole drilling machine comprising a frame having telescopically adjusted legs, an elongated member pivotally attached to said frame and shiftable at a radius from said pivot point, a stabilizer attached to the outer end of said member having a telescopically adjusted leg in contact with the ground, a wheel carried by said leg, a crank shaft rotatably mounted upon said member provided with a fixedly secured gear at one end thereof, a sleeve slideable longitudinally upon said crank shaft and provided with a plurality of gears of different diameters fixedly secured thereto, a bracket loosely disposed upon said sleeve intermediate said gears and provided with a rotatably mounted gear engageable with a smaller gear of said sleeve, a pipe shaft vertically mounted upon the outer end of said member and provided with a longitudinal slot approximately the length thereof, a bar rotatably disposed within said pipe shaft and provided with a groove, a gear fixedly secured to said last named sleeve engageable with the gear upon the end of said crank shaft, a collar carried by said last named sleeve, a bracket loosely engageable with said bar and with said crank shaft for sustaining the gears thereof in meshing contact, and means for shifting the sleeve of said crank shaft in either direction whereby the gears thereof will be caused to alternately engage with the gear of said pipe shaft whereby said auger will penetrate the ground and be removed therefrom without reversing the direction of its rotation when said crank shaft is actuated.
